APPARATUS FOR TESTING PACKING MATERIALS

Raymond W. Justice, Youngstown, Ohio

Application October 13, 1949, Serial No. 121,187

6 Claims. (Cl. 73—9)

1

This invention relates to testing apparatus and more particularly to apparatus for determining the frictional resistance to sliding movement created by fluid-tight packings in machine elements such as hydraulic pistons, for example. The efficiency of fluid-sealing packings is determined not only by the ability of the packing to contain the applied fluid pressures but also by the amount of frictional resistance to movement of the relatively movable parts resulting from the presence of the packing. It is therefore desirable to be able to determine and predict the extent of frictional resistance which can be expected from the installation of different kinds of packings in hydraulic and other machinery. It is accordingly the primary object of the invention to provide a practical apparatus which is operative to accurately indicate relative frictional resistances set up by different packing materials and acting under widely varying operational pressures.

A further object of the invention is the provision in apparatus of the kind mentioned above of an improved arrangement whereby all factors other than the friction factor supplied by the packing being tested are automatically cancelled out so that a direct comparative reading of the frictional resistance created by the packing is made possible.

The above and other objects and advantages of the invention will become apparent upon consideration of the following detailed specification and the accompanying drawing wherein there is disclosed a preferred embodiment of the invention.

In the drawing:

Figure 1 is a side elevation, partly in section, of a testing machine constructed according to my invention; and

Figure 2 is a fragmentary longitudinal section, on an enlarged scale, of the apparatus of Figure 1.

The apparatus illustrated comprises an internally honed cylinder 10 having end members 11 and 12 which are secured to the cylinder 10 by any suitable quick-disconnecting means, not shown, as for example, conventional cap screws. End members 11 and 12 are centrally bored in axial alignment to slidably receive the rods 13 and 14 of a piston assembly now to be described.

Referring more particularly to Figure 2 it will be noted that the piston assembly consists essentially of two parts, 15 and 16, which are locked together by a screw threaded plug 17 which is integral with the part 15 and is screw-threadedly received in a central bore formed in the part 16.

It should be noted that the plug 17 extends outwardly and is integral with a square boss 18 extending outwardly from the face of the part 15 and formed integrally therewith. The outer periphery of the piston part 15 is recessed inwardly from the face thereof as shown at 19 to receive a packing assembly which may consist of rigid end rings 20 and 21 of bronze, for example, and intermediate chevron packing rings 22 of leather, for example. A similar recess 23 is formed in the outer periphery of the piston part 16 and this latter part is also formed with an axial recess 24 to receive the outer end portion of the boss 18.

To retain the packing ring assemblies in the recesses 19 and 22 and to supply fluid pressure thereto in axial thrust relation I employ a spacing washer 25 which is centered over the boss 18 and which is provided with a plurality of interconnected radial and axial bores 26 and 27, respectively. The ring or washer 25 may be constructed of either bronze or steel and its outside diameter is somewhat less than the internal diameter of the cylinder 10 so as not to bear thereagainst. This is also true of the outer diameters of the parts 15 and 16.

To conduct fluid pressure into the passages 26 and 27 of the washer 25 the rod 13 and piston part 15 are provided with a centrally disposed bore 28 which terminates in a radially extending opening 29 in which is attached a fitting 30 connected, in turn, to a flexible supply conduit 31. Radial passages are formed in the boss 18 to connect the bore 28 with the bores 26 in the washer 25 and it should be apparent that fluid pressure supplied by the conduit 31 will enter through passages 28, 26 and 27, in sequence against the flat bases of the rigid rings 21 of the packing assemblies mounted on the piston whereby these assemblies will be subjected to axially applied fluid pressures in substantially the same manner as fluid pressures are applied under actual operating conditions in conventional cylinders, for example.

It should be observed that the bore 28 in piston part 15 extends entirely through the screw plug 17. In axial alignment with this bore 28 is a bore 32 in rod 14 and piston part 16 terminating in a radially extending opening 33 to which is attached a pressure gauge 34. In this manner an accurate indication of the fluid pressure actually applied to the packing assemblies on the piston may be obtained.

Extending outwardly of the end housing 12 is a tube 35 having a longitudinally extending slot therein to slidably receive a jack hook 36.

The part 36 is provided with a threaded bore to receive a screw-threaded rod 37 which is rotatable in the tube 35 so that upon rotation of the rod 37 the hook 36 will be drawn along the tube 35 as will be understood. A hand crank 38 is keyed in the outer exposed end of the rod 37 whereby the latter may be rotated. Detachably secured to the exposed end of the piston rod 14 outwardly of the passage 33 is a hook-line member 39 adapted to be interconnected with the jack hook 36 by a dynamometer 40 having a connecting link 41 at each end thereof. The dynamometer 40 is a conventional instrument arranged to give a direct reading on its dial of the pulling force exerted on the two connecting links 41. It should therefore be apparent, upon inspection of Figure 1, that upon assembly and arrangement of the apparatus as shown and upon turning the crank 38 in a direction to move the hook 36 outwardly of the cylinder 10 the dynamometer 40 will indicate the force required to move the piston 15, 16 in the cylinder 10.

I preferably provide a unitary self-contained fluid pressure supply for the test apparatus of my invention to make the apparatus portable and, in practice, the supply unit may be in the form of a combined reservoir, pump and valve assembly as shown at 42. Such combined apparatus is conventional in the art and includes a pump, not shown, to which is connected an operating lever 43, the pump having an outlet which in the present case is connected to the flexible conduit 31. The fluid pressure supply unit further includes a valve, also not shown, having an actuating lever 44 which upon being depressed is operative to connect the conduit 31 with the reservoir in the unit 42 whereby the fluid pressure in the conduit 31 may be relieved as desired. In accordance with usual practice a suitable check valve is associated with the outlet of the pump in unit 42 to maintain the desired pressure built up in the test cylinder by manipulation of the lever 43.

When it is desired to test any particular style of packing or kind of packing material specimens of the proper size to fit in the recesses 19 and 23 of the piston parts 15 and 16 are first either procured or prepared. The test apparatus is disassembled by removing the fitting 30 and the end housing 11 which allows the end housing 11 and cylinder 10 to be removed, thus exposing the piston of the apparatus. The piston may now be dis-assembled by unscrewing the part 15, thereby exposing an axial end of each of the recesses 19 and 23 to allow the packing ring assemblies to be tested to be properly mounted on the piston parts 15 and 16. The piston is now re-assembled with the spacing washer 25 in proper position between the two packing ring assemblies. The cylinder 10, end housing 11 and fitting 13 will now be re-assembled so the test can proceed. At the start, the piston 15, 16 may be moved to the left end of the cylinder 10, as viewed in Figure 1. By means of the pump in unit 42 fluid pressure of a desired value is applied to the packing assemblies to be tested and upon the pressure reaching a desired value as indicated by the meter 34 the crank 38 is actuated to draw the piston and packing assembly longitudinally through the cylinder 10 and the force required to do so is measured by the dynamometer 40. This force measurement gives an accurate indication of the frictional resistance caused by the packing assemblies under the particular fluid pressure applied since the frictional resistance at the other sliding joints of the apparatus is

negligible due to the loose tolerance provided between the cylinder and piston assembly and between the end housings 11 and 12 and the rods 13 and 14, respectively. The axial length of each of the two packing ring assemblies is that recommended for the particular diameter of the cylinder of the test apparatus so that the force indicated by the dynamometer 40 will be twice the frictional resistance which can be expected from one of the packing ring assemblies when installed in a conventional cylinder and piston combination. By taking comparative readings at different applied fluid pressures and with different packings and packing materials it is possible to make a complete analysis of different materials under widely varying applied fluid pressures, as will be understood.

In certain types of packing the frictional resistance to sliding movement may be greater in one direction than in the other or opposite direction and it is therefore not possible to get a direct reading of the frictional resistance simply by halving the force indicated by the dynamometer and in such cases the apparatus allows me to install a packing assembly of known and proven friction value on one part of the piston assembly while the packing to be tested is installed on the other part of the piston assembly. By subtracting the known value from the dynamometer reading the frictional resistance of the packing under test can be readily determined and since the piston and rod assembly including the parts 13, 14, 15 and 16 are readily reversible as a unit with respect to the cylinder, readings can readily be obtained for either direction of movement of the packing assembly under test.

I also contemplate that the central bosses on the end members 11 and 12 of the cylinder assembly may be enlarged and recessed in a manner analogous to the structure shown in Figure 1 of my copending application S. N. 121,188 filed October 13, 1949, whereby the apparatus of the invention may also be rendered suitable for testing piston rod packings in addition to piston packings. In such use of the modified apparatus either one or both of the packing assemblies on the piston would be omitted to enable the full application of the desired pressure against either or both of the piston rod packings mounted in the end members 11 and 12.

An important feature of the apparatus of the invention is the ability to maintain constant the fluid pressure applied even while the piston is in motion and while a continuous reading of the dynamometer 40 is being taken. Thus, not only is it possible to measure the starting friction but also the operating or moving friction of the packing being tested.

The above specifically described embodiment of the invention should be considered as illustrative only as many changes may be made therein without departing from the spirit or scope of the invention. Reference should therefore be had to the appended claims in determining the scope of the invention.

I claim:

1. In apparatus for measuring the frictional resistance to sliding movement of piston-type of packings comprising in combination a cylinder, a piston slidable in said cylinder and having an outwardly extending piston rod, a pulling device adapted to be moved outwardly along the axis of said rod, a dynamometer interconnecting said pulling device and said rod and operative to measure the force required to move said rod and

piston, said piston having an annular recess to receive a packing ring assembly to be tested, fluid passages in said piston to conduct fluid under pressure to one axial face of said packing ring assembly, and means to conduct fluid under pressure into said passages.

2. In apparatus for measuring frictional resistance to sliding movement of piston-type packings comprising in combination a cylinder, a piston assembly slidably mounted in said cylinder comprising a pair of separable members, each having an annular recess to receive a packing ring assembly to be tested, said recesses extending axially outward from the inner adjacent faces of said members and terminating in flanges adjacent the outer ends of said members, a spacing washer carried by said piston and separating said recesses, said spacing washer having radial and axial passages to conduct fluid pressure to the inner faces of the packing assemblies contained in said recesses, means to conduct fluid under pressure into said passages, means to move said piston axially in said cylinder, and means to measure the force required to move said piston in an axial direction.

3. In apparatus for measuring frictional resistance to sliding movement of piston-type packings comprising in combination a cylinder, a piston slideable in said cylinder and comprised of two separable members each having a rod extending outwardly therefrom and each having an annular packing-ring-receiving recess extending axially outward from the inner face thereof and terminating at a flange, centrally disposed passages in said rods and members in communication with each other, means in said piston to conduct fluid pressure from said passages onto the inner axial faces of packing ring assemblies mounted in said recesses, the passages in said rods having terminals positioned outwardly of said cylinder, a flexible conduit connecting with the passage terminal on one of said rods to conduct fluid pressure thereinto, a pressure gauge mounted on the other of said rods and connecting with the passage terminal thereon, means to slide said piston in said cylinder, and means to measure the force required to slide said piston in said cylinder.

4. In apparatus for testing ring-like packing materials a piston comprising a plug-like member having an annular packing ring receiving recess in its outer periphery extending axially inward from one end thereof, a boss on said member extending centrally and axially outward of said end and adapted to mount a separating washer, a separating washer on said boss, a screw-threaded extension integral with and projecting centrally and axially outward of said boss, a second plug-like member having a thread-

ed bore to receive said threaded extension and having an annular recess in its outer periphery to receive a second packing ring assembly, said last mentioned recess being open axially to said washer whereby upon assembly of said piston said washer is operative to separate and retain said two packing ring assemblies, and a piston rod connected with one of said members.

5. Apparatus according to claim 4 further characterized in that said piston rod and connected member are provided with a centrally disposed bore for the passage of fluid pressure, said boss and washer having radially disposed passages therein in communication with said first mentioned passage, and said washer having axially disposed passages in communication with said radial passages whereby fluid under pressure may be brought to bear against the adjacent end faces of said packing ring assemblies.

20 6. In apparatus for measuring the frictional resistance to longitudinal sliding movement of piston-type packings the combination of a cylinder, a piston assembly slideable longitudinally in said cylinder and having a pair of rigidly interconnected piston-like parts spaced longitudinally to define an annular space therebetween, means on one of said piston-like parts to receive a piston-type of packing to be tested with the fluid pressure existent in said annular space acting on an axial end of said packing in one longitudinal direction while said other piston-like part restrains longitudinal movement of fluid from said annular space in the opposite longitudinal direction, means forming a fluid passage communicating with said annular space whereby fluid under predetermined pressure may be supplied to said annular space, means to move said piston assembly longitudinally in said cylinder, and means to measure the force exerted by said means to move on said piston assembly during longitudinal movement of said assembly.
